Primary Examiner — Prabhakar Deshmukh(74) *Attorney, Agent, or Firm* — Hackler Daghighian & Martino(57) **CLAIM**

The ornamental design for a door terminal, as shown and described.

DESCRIPTION

FIG. 1 is a front elevation view of a door terminal embodying my new design;

FIG. 2 is a rear elevation view of FIG. 1;

FIG. 3 is a left side view of FIG. 1;

FIG. 4 is a right side view of FIG. 1;

FIG. 5 is a top plan view of FIG. 1;

FIG. 6 is a bottom plan view of FIG. 1; and,

FIG. 7 is a front perspective view of the FIG. 1.

The broken lines depict environmental subject matter, are for illustration only and form no part of the claimed design.
